UNITED STATES PATENT OFFICE.

FRANK H. McSWEENEY, OF HOUSTON, TEXAS.

LINT-COTTON CONVEYER.

Application filed March 1, 1926. Serial No. 91,649.

This invention relates to new and useful improvements in a lint cotton conveyer.

One object of the invention is to provide, in an apparatus of the character described, 5 a conveyer flue, of novel formation with novelly arranged branches connecting it with the linters and through which the lint cotton may be conveyed from the linters to the condenser.

10 Another object of the invention is to provide a lint conveying flue, provided with branches which lead into said flue from the linters, all of such construction and arrangement that the lint will follow a 15 straight course through the flue to the condenser and will not be subjected to a whirling motion as it passes through said flue and consequently will be delivered to the condenser in a loose and uniform mass 20 and will not collect in masses of unequal density.

With the above and other objects in view this invention has particular relation to certain novel features of construction, operation, and arrangement of parts, an example 25 of which is given in this specification, and illustrated in the accompanying drawings, wherein:—

Figure 1 shows a side elevation of a linter 30 showing the lint flue in cross section, and the branches leading from the linters to said flue.

Figure 2 shows a rear view thereof, showing 35 said flue and branches in elevation, and

Figure 3 shows a fragmentary plan view of said flue showing the adjacent ends of 40 said branches.

Referring now more particularly to the drawings, wherein like numerals of reference 45 designate similar parts in each of the figures, the numeral 1 designates a flue which is preferably formed rectangular in cross section through which the lint cotton is conveyed from the linters 2, of well known 50 construction, to the condenser (not shown). In practice the linters are disposed in spaced series with the flue 1, arranged above and between said series, the said linters being preferably arranged in pairs, one on 55 each side of the flue. The flue 1 is formed with sections, each section being smaller than the adjacent section toward the condenser so that the capacity of the flue is gradually increased as it approaches the condenser.

Leading from each linter are the lint feed

flues 3, 3, the feed flues from each pair of linters entering the outer end of the corresponding section of the flue 1 as illustrated in Figure 3, the feed flues from one 60 linter entering the flue 1, on the opposite side of said flue from the feed flues entering the flue 1 from the corresponding linter of said pair. The feed flues 3 are preferably 65 cylindrical but their delivery ends are flattened as at 4, and discharge into the main flue 1, said discharge ends of each pair being arranged alongside, one above the other and these discharge ends are turned into substantially parallel arrangement with respect to the flue 1 so that the lint will be 70 delivered from them into the flue 1 in a longitudinal course rather than diagonally. This arrangement prevents the lint delivered from the feed flues from setting up a whirling motion and thus becoming formed into 75 masses of varying densities and permits the lint from all of the feed flues to move in a substantially uniform mass along the flue 1.

Since the flue 1, gradually enlarges, section by section, the current of air passing therefrom will not be liable to start a whirling movement and consequently the lint will not be thrown into masses of varying densities. The rectangular form of the flue 1 also 80 assists in preventing this whirling movement of the lint.

What I claim is:—

1. A lint flue formed of sections and gradually enlarging toward its discharge 90 end and a pair of feed flues entering the inlet ends of said sections on each side.

2. A lint flue formed of sections, each section being larger than the preceding section and a pair of feed flues entering the inlet 95 ends of each flue section on each side.

3. A lint flue formed of sections, each section being larger than the preceding section and a pair of feed flues entering the inlet ends of the flue section on each side, each 100 pair of feed flues having wide discharge ends arranged adjacent.

4. A lint flue, rectangular in cross section, and formed of a plurality of sections, each section being larger than the preceding section, and feed flues entering the inlet ends 105 of said sections.

5. A lint flue, rectangular in cross section, and formed of sections, each section being larger than the preceding section, feed flues 110 having wide discharge ends turned into approximately parallel relation with said lint

flue and entering the inlet ends of said sections.

6. A lint flue, rectangular in cross section, and formed of a plurality of sections, each section being larger than the preceding section, and feed flues entering the inlet ends of said sections, said feed flues being arranged in pairs, the discharge ends of the respective pairs lying adjacent.
- 10 7. A lint flue, rectangular in cross section, and formed of sections, each section being larger than the preceding section, feed flues having wide discharge ends turned into approximately parallel relation with said lint flue and entering the inlet ends of said sections, said feed flues being arranged in pairs the discharge ends of the respective pairs lying adjacent.

8. A lint flue whose capacity increases from its inlet to its discharge end and whose bottom is flat, feed flues arranged in pairs and discharging into said lint flue, the entering ends of the respective pairs of feed flues lying adjacent.

25 9. A lint flue whose capacity increases from its inlet to its discharge end and whose

bottom is flat, feed flues arranged in pairs, and discharging into said lint flue, the entering ends of the respective pairs of feed flues lying adjacent and being substantially parallel with the lint flue.

10. A lint flue formed of sections, a section being larger than the preceding section, the bottom of said flue being substantially flat and horizontal, and a pair of feed flues having wide discharge ends entering the inlet of the larger flue section, on each side.

11. A lint flue formed of sections, a section being larger than the preceding section, the bottom of said flue being flat and horizontal, and a pair of feed flues having discharge ends entering the inlet end of the larger flue section, on each side.

12. A lint flue formed of sections, a section being larger than a preceding section, and a pair of feed flues having wide discharge ends entering the inlet end of the larger flue section on each side, and parallel therewith.

In testimony whereof I have signed my name.

FRANK H. McSWEENEY.
